UNITED STATES PATENT OFFICE

93,172

DESIGN FOR A CASING FOR A GRINDING MILL

John C. Kopf, New York, N. Y., assignor to Jabez Burns & Sons, Inc., New York, N. Y., a corporation of New York

Application June 19, 1934, Serial No. 52,244

Term of patent 14 years

To all whom it may concern:

Be it known that I, JOHN C. KOPF, a citizen of the United States, residing at New York, in the county of New York, State of New York, have invented a new, original, and ornamental Design for Casing for a Grinding Mill, of which the following is a specification, reference being had to the accompanying drawing, forming part thereof, in which:

Fig. 1 is a front elevation;

Fig. 2 is a top plan.

I claim:

The ornamental design for a casing for a grinding mill substantially as shown.

JOHN C. KOPF.
